AIRPORT REFLECTOR

Wallace A. Stanley, Bloomfield Hills, Mich., assignor to
Reflex Corporation of America, Troy, Mich., a corpora-
tion of Michigan

Filed Nov. 14, 1966, Ser. No. 4,662

Term of patent 14 years

(Cl. D72—1)

FIG. 1

FIG. 3

FIG. 2

FIG. 4

FIG. 1 is a perspective view showing two sides of an airport reflector embodying my new design, the sides not shown being the same as the sides shown.

FIG. 2 is a fragmentary sectional view taken along the line 2—2 in FIG. 1.

FIG. 3 is a fragmentary sectional view taken along the line 3—3 in FIG. 1.

FIG. 4 is a fragmentary rear elevational view of one of the reflectors with the back removed.

The dominant features of the design are shown in solid lines.

I claim:

The ornamental design for an airport reflector, sub-
stantially as shown and described.
